UNITED STATES PATENT OFFICE

1,939,473

PIPE

Apollo Torrese, Philadelphia, Pa., assignor of twenty-five per cent to Joseph Apilungo, Philadelphia, Pa.

Application March 3, 1933. Serial No. 659,519

9 Claims. (Cl. 131—12)

This invention relates to pipes, and has for an object to provide a pipe having improved means for providing elongated passages through the stem from the bowl to the mouthpiece.

5 A further object of the invention is to provide a pipe having a bowl and mouthpiece with interconnecting stem and passageways through the stem returning upon themselves to form ducts from the bowl to the mouthpiece several times 10 longer than the stem.

A further object of the invention is to provide a pipe having a bowl and mouthpiece with interconnecting stem with a plurality of chambers located between the bowl and the mouthpiece

15 with the stem provided with a conduit communicating at intervals in its extent with the several chambers.

A further object of the invention is to provide a pipe having a stem formed at one end as a ring 20 with a bowl inserted into the ring from one side, a cap inserted into the ring from the opposite side, said cap and bowl being interconnected by screw threads which form the sole means for clamping the bowl to the stem and together clamp the 25 ring firmly between the cap and the bowl.

A further object of the invention is to provide a pipe having a stem with a fluted filler therein, the grooves of said fluting forming with the stem a plurality of smoke passages which communicate 30 respectively with a plurality of chambers within the stem, and after traversing the length of the stem a number of times communicate directly with a mouthpiece carried by the stem.

A further object of the invention is to provide 35 a pipe having a stem otherwise hollow but filled with a filler having corrugations running longitudinally thereof, each coacting with the interior walls of the stem for smoke passages, one of which is in communication with a chamber underlying 40 the bowl, another in communication with two chambers spaced at opposite ends of the stem with a third passage through said filler communicating directly with the mouthpiece.

The invention, therefore, comprises a hollow 45 stem which is provided with a filler having longitudinal corrugations and a longitudinal bore, the hollow stem providing chambers at opposite ends of the filler, one chamber being in communication with one of the grooves and with the bore, the 50 other chamber communicating with a conduit which in turn communicates with the chamber underlying the bowl into which chamber a communicating passage from the bowl also opens.

In the drawing,
55 Figure 1 is a view of one embodiment of the

pipe taken in longitudinal section substantially diametrical of the bowl and stem.

Figure 2 is a sectional view taken on line 2—2 of Figure 1.

Figure 3 is a longitudinal sectional view of a 60 modification taken diametrically of the stem and bowl.

Figure 4 is a sectional view taken on line 4—4 of Figure 3, and

Figures 5 and 6 are respectively transverse 65 sectional views taken on lines 5—5 and 6—6 of Figures 1 and 3.

Like characters of reference indicate corresponding parts throughout the several views.

The improved pipe, which forms the subject- 70 matter of this application, is shown in the drawing in two embodiments differing slightly in the matter of bowl attachment. In both, stems 10 are made hollow with a filler 11 inserted into the hollow sleeve. This filler 11 has grooves 12 and 75 13 running longitudinally thereof and formed in the otherwise cylindrical surface of the filler. At Figure 1, the groove 11 terminates slightly short of the end and communicates with an inclined passage 14, while at Figure 3 the termination is nearer the end and terminates at inclined passage 15.

The filler 11 is also provided with an axial bore 16 enlarged at one end to receive the tube 17 carried by the mouthpiece 18. In the type shown 85 at Figure 1, the stem is formed as a ring 19, and preferably, though not necessarily, with rabbets 20 about the opposite sides. The bowl 21 is provided with a neck 22 which extends down inside of the ring 19 and with a groove 23 which 90 coacts with the rabbet 20.

A cap 24 is provided with a groove 25 coacting with the rabbet 20 on the opposite side of the ring. The cap is also provided with a sleeve 26, which fits snugly within the ring, and is provided 95 internally with screw threads which inter-engage with similar screw threads on the neck 22, so that the bowl 21 is held in air- and smoke-tight relation to the ring by merely rotating the cap 24 to exert tension upon the neck 22.

The bowl is provided with a passage 27, and preferably, though not necessarily with a tube 28 which extends down into a chamber 29 underlying the neck 22. One side of the neck 22 is provided with a longitudinal passage 30, which 105 forms communication between the chamber 29 and the passage 14 in the stem. The sleeve 26 of the cap 24 is made somewhat shorter than the width of the ring 19, so that a passage is provided entirely around the neck 23 above the 110

end of the cap 24, which passage communicates with the conduit 14, so that no matter how the bowl may be arranged rotatably relative to the ring 19, the passage 14 will always communicate 5 through the chamber and through the passage 30 with the chamber 29.

As shown at Figure 3, the bowl 31 is connected directly by screw threads with the chamber 32, such screw threads being shown at 33. As in the 10 case shown at Figure 1, the bowl is provided with the passage 27 and tube 28, which communicates with the chamber 32. A passage 30 is also provided in the neck 22' here shown, and a passage is formed entirely about said bowl in communication with the passage 15 of the stem. In the embodiment shown at Figure 1, the mouthpiece 18 is shown as connecting with the stem by screw threads, and at Figure 3, the connection is shown the same, both being shown at 34. Instead, however, of the connection and disconnection of the bowl from the stem as shown at 20 Figure 1, in Figure 3, the connection is at the slip-joint 35 with the filler 11 screw threaded at 36 to receive a short stem part 37 carried 25 integrally by the member including the chamber 32.

As arranged at Figure 1, in addition to the chamber 29, chambers 38 and 39 are provided. At Figure 3, the chamber 39 is substantially identical, but the chamber 38', differs slightly in that there is a communicating passage at 40 from the stem section 37 to the chamber 32, which is filled by the end 41 of the filler. The central bore 16 of the filler shown at Figure 3 is also 35 provided with lateral openings 42 which communicate with this chamber 38'.

In operation, in the type shown at Figure 1, smoke will pass from the bowl 21 through the passage 27 and tube 28 to the chamber 29, then 40 upwardly through the passage 30 to the passage 14 to the chamber 39, through the passage 13 to the chamber 38, through the central bore 16 and tube 17 to the mouthpiece 18.

In the type shown at Figure 3, the smoke will 45 pass through the bowl 31, through the passage 27 and tube 28 to the chamber 32, then through the passages 30 and 15, through the chamber 39, through the passage 13 to the chamber 28, through the lateral openings 42 to the bore 16 of 50 the filler, and through the tube 17 of the mouthpiece. In its travel, the smoke will, therefore, pass through passages substantially three times the length of the stem, and will, therefore, be subjected to cooling influences the equivalent of the 55 stem nearly three times as long. It will also pass through the three chambers 29, 38 and 39, each of which chambers is readily accessible.

In the type shown at Figure 1, the removal 60 of the mouthpiece 18 will make the chamber 39 accessible. By the removal of the cap 24, the bowl and cap may be removed from the ring 19, and the chamber 29 opening off from the cap will be easily accessible as will also be the chamber 38 and passage 14.

65 In the type shown at Figure 3, the mouthpiece is similarly removed, but the stem is disconnected at the slip-joint 35 by the use of the threads 36. The removal of the bowl in this manner will remove the filler 11 from the chamber 38' and will 70 also open the passage 40 between the chambers 38' and 32, whereby both of these chambers are accessible for cleaning.

The invention is hereby claimed as follows:—

75 1. A pipe comprising a bowl having an underlying communicating chamber, a stem having a

conduit in communication with the chamber, a removable filler for the stem having a passage restricting the communication with the chamber to said passage, said filler forming a second chamber within the stem also communicating with the passage, said filler also forming a third chamber within the stem and having a second passage forming communication between the second and third chambers, and a mouthpiece having a tube passing through the second chamber, said filler further having a conduit forming communication between the third chamber and the tube.

2. A pipe comprising a bowl having a threaded part extending downwardly into an underlying communicating chamber, a stem having a conduit in communication with the chamber, a removable filler for the stem having a passage restricting the communication with the chamber to said passage, said filler forming a second chamber within the stem also communicating with the passage, said filler also forming a third chamber within the stem and having a second passage forming communication between the second and third chambers, and a mouthpiece having a tube 100 passing through the second chamber, said filler further having a conduit forming communication between the third chamber and the tube.

3. A pipe comprising a bowl having a threaded part extending downwardly into an underlying communicating chamber, a stem having a conduit in communication with the chamber through a slot formed in the threaded part, a removable filler for the stem having a passage restricting the communication with the chamber to said 105 passage, said filler forming a second chamber within the stem also communicating with the passage, said filler also forming a third chamber within the stem and having a second passage forming communication between the second and third chambers, and a mouthpiece having a tube passing through the second chamber, said filler further having a conduit forming communication between the third chamber and the tube.

4. A pipe comprising a bowl having an underlying communicating chamber, a stem having a conduit in communication with the upper part of the chamber, a removable filler for the stem having a passage restricting the communication with the chamber to said passage, said filler forming a 120 second chamber within the stem also communicating with the passage, said filler also forming a third chamber within the stem and having a second passage forming communication between the second and third chambers, and a mouthpiece having a tube passing through the second chamber, said filler further having a conduit forming communication between the third chamber and the tube.

5. A pipe comprising a bowl having a threaded part extending downwardly into an underlying communicating chamber, a threaded collar engaging the threaded part of the bowl and maintaining the bowl in position, a stem having a conduit in communication with the chamber, a removable filler for the stem having a passage restricting the communication with the chamber to said passage, said filler forming a second chamber within the stem also communicating with the passage, said filler also forming a third chamber within the stem and having a second passage forming communication between the second and third chambers, and a mouthpiece having a tube passing through the second chamber, said filler further having a conduit forming 140 communication between the third chamber and the tube.

communication between the third chamber and the tube.

6. A pipe comprising a bowl having an underlying communicating chamber, a stem having a conduit in communication with the chamber, a removable filler for the stem having a passage restricting the communication with the chamber to said passage, said filler forming a second chamber within the stem also communicating with the passage, said filler also forming a third chamber within the stem and with an opening from the third to the first chamber, said filler having a plug normally closing said opening and having a second passage forming communication between the second and third chambers, and a mouthpiece having a tube passing through the second chamber, said filler further having a conduit forming communication between the third chamber and the tube.

20 7. A pipe comprising a bowl having a threaded part extending downwardly into an underlying communicating chamber, a stem having a conduit in communication with the upper part of the chamber, a removable filler for the stem having a passage restricting the communication with the chamber to said passage, said filler forming a second chamber within the stem also communicating with the passage, said filler also forming a third chamber within the stem and with an opening from the third to the first chamber, said filler having a plug normally closing said opening and having a second passage forming communication between the second and third chambers, and a mouthpiece having a tube passing through the second chamber, said filler further having a conduit forming communication between the third chamber and the tube.

25 8. A pipe comprising a bowl having a threaded part extending downwardly into an underlying

communicating chamber, a threaded collar engaging the threaded part of the bowl and maintaining the bowl in position, a stem having a conduit in communication with the upper part of the chamber through a slot formed in the threaded part, a removable filler for the stem having a passage restricting the communication with the chamber to said passage, said filler forming a second chamber within the stem also communicating with the passage, said filler also forming a third chamber within the stem and having a second passage forming communication between the second and third chambers, and a mouthpiece having a tube passing through the second chamber, said filler further having a conduit forming communication between the third chamber and the tube.

30 9. A pipe comprising a bowl having a threaded part extending downwardly into an underlying communicating chamber, a threaded collar engaging the threaded part of the bowl and maintaining the bowl in position, a stem having a conduit in communication with the upper part of the chamber through a slot formed in the threaded part, a removable filler for the stem having a passage restricting the communication with the chamber to said passage, said filler forming a second chamber within the stem also communicating with the passage, said filler also forming a third chamber within the stem and with an opening from the third to the first chamber, said filler having a plug normally closing said opening and having a second passage forming communication between the second and third chambers, and a mouthpiece having a tube passing through the second chamber, said filler further having a conduit forming communication between the third chamber and the tube.
